UNITED STATES PATENT OFFICE

WILLIS J. MA GIRL, OF BLOOMINGTON, ILLINOIS, ASSIGNOR TO P. H. MA GIRL FOUNDRY AND FURNACE WORKS, OF BLOOMINGTON, ILLINOIS, A FIRM COMPOSED OF JAMES D. MA GIRL, IDA DALTON, AND GERTRUDE JOHNSTON

BOILER

Application filed November 26, 1930. Serial No. 498,482.

This invention pertains to boilers and more particularly to those employed primarily for domestic purposes wherein gas or oil is employed as the fuel. The construction is such that the boiler may be used in connection with water, steam or vapor heating systems.

The main object of the invention is to provide means, in a boiler of the water tube type, whereby the water is caused to circulate in such paths that no cross currents will be set up thus insuring a rapid circulation throughout the boiler.

A further object is to provide a sectional and light structure which facilitates ease of handling and the ready passage of the parts through a usual doorway.

A still further object is to provide a structure which affords ready accessibility to the tubes whereby they may be removed and replaced with a minimum of trouble.

Another object resides in so shaping and forming the boiler and its enclosure that they are of unit form whereby two or more units may be readily assembled and connected so as to produce a structure which may be of the desired and necessary capacity.

With these and other objects and advantages, which will hereinafter appear in view, reference is made to the annexed drawings wherein—

Figure 1 is a perspective view of the boiler with the upper casing removed;

Figure 2, a vertical sectional view on the line II—II of Figure 3;

Figure 3, a similar view on the line III—III of Figure 2;

Figures 4 and 5, transverse sectional views on the lines IV—IV and V—V respectively of Figure 2; and

Figure 6, a like view on the line VI—VI of Figure 3.

In the drawings 1, 2, 3 and 4 denote rectangular metallic sections secured together at their adjacent edges to produce the square base of the boiler. The sections are each provided at their lower edge with a foot flange 5 and at their upper edge with an inwardly extending flange 6 the upper face whereof at its inner edge is countersunk (see Figures 2

and 3) for a purpose which will presently appear.

Furthermore, each of said sections is provided with internally extending cross ribs, as 7, which, when the sections are assembled, form in effect continuous ribs between which refractory blocks 8 are placed, forming a fire box. Within said box may be placed a suitable burner, oil or gas as desired, the opening for the feed pipe of which may extend through any of the base sections.

One of said sections, as 4, will have a door or removable section 9 associated therewith to afford access to the burner.

Surmounting the fire box or base and resting upon the inwardly extending flange 6 at one side thereof is a base header 10 having two upwardly extending water legs 11 and 12 which are connected at their upper ends by suitable nipples 13 and 14 respectively with the upper header denoted generally by 15.

The upper and lower headers 10 and 15 are also connected by a series of coils 16 and 17, the ends of one set of coils, both at the upper and lower portions thereof, being slightly shorter than those of the other coils so that they may enter or be connected to the lower water box or header 10 at the rear and front thereof and likewise out of common vertical plane at the upper end where they communicate with the upper header 15.

The header 15 is provided with a dome-shaped member 18 at its upper side and an off-take pipe 19 is connected with the upper portion thereof.

A return pipe 20 opens into the lower header 10.

As will be best seen upon reference to Figure 3, the water passes from the header 10 through the various coils 16 and 17 and upwardly into the upper chamber or header 15, thence outwardly through the pipe 19 and back to the pipe 20. In case the boiler is used as a steam generator the water level will be maintained somewhat above the outlets of the upper end of the coils and the water will then flow from said upper ends laterally to the connections 13 and 14 and down the water legs 11 and 12 to the lower header 10. In this way it will be seen that there is sub-

stantially no interference with the flow of the water by setting up cross currents as frequently occurs in many boiler constructions.

Products of combustion pass upwardly from the chamber in which the coils are located through flues 21 and 22 which pass upwardly through the header 15 and discharge into a chamber 23 from which there extends the ordinary off-take flue or chimney pipe 24.

10 The upper header 15 is supported upon that side opposite the water legs 11 and 12 by posts or columns 25 and 26 (Figure 4) which are secured to the header and to the furnace base in any suitable manner. The 15 lower header, the water legs, and the upper header are enclosed within a metallic casing 27 made up in sectional form and provided upon its inner surface with a layer of insulating material 28. This enclosure, which is 20 the heating chamber, is provided with a door, as 29, (Figure 2) to afford access to the coils so that they may be removed and replaced should occasion require.

The boiler will, of course, be provided with 25 suitable gauges, both steam and water level, so that it may be used either as a steam boiler proper or as a water heating boiler.

Various units may be assembled side by side and with this in view the lower header 30 10 is provided with openings normally closed by screw plugs 30 and 31, either one of which may be removed when sections are placed adjacent thereto and suitable nipples employed to bring about connection of one lower header 35 with another. So too the upper header 15 may have an opening formed therein normally closed by a screw plug 32.

What is claimed is:

In a boiler, the combination of a base; 40 a heating chamber mounted thereon; a header extending along one side only of the base within said chamber, said header having a water leg extending upwardly from each end of said header; an upper header connected to 45 and in communication with the water legs, said upper header being of such dimensions as to substantially equal the transverse dimensions of the heating chamber and closing the upper portion thereof and said header being provided with at least one flue extending therethrough for the passage of combustion gases, there being a vented chamber formed above the upper header for the reception of the combustion gases; a pair of 50 posts extending upwardly from the base to the side of the upper header opposite the water legs and forming with said legs the support for said upper header; and a series of 55 coils within said heating chamber connecting the headers.

In testimony whereof I have signed my name to this specification.

WILLIS J. MA. GIRL.
